UNITED STATES PATENT OFFICE

109,183

DESIGN FOR A TEXTILE FABRIC

Mac Etlinger, New York, N. Y.

Application February 19, 1938, Serial No. 75,270

Term of patent 3½ years

To all whom it may concern:

Be it known that I, Mac Etlinger, a citizen of the United States of America, residing in city of New York, county of New York, and State of New York, have invented a new, original, and ornamental Design for a Textile Fabric, of which the following is a specification, reference being had to the accompanying drawing, forming part thereof.

The figure on the drawing is a plan view of a textile fabric showing my new design.

The design unit is contained between the dot and dash lines, which unit is repeated in regular succession as indicated by the extensions beyond the unit boundaries.

I claim:

The ornamental design for a textile fabric, substantially as shown and described.

MAC ETLINGER.
